UNITED STATES PATENT OFFICE.

EDWARD D. STACY, OF CHICAGO, ILLINOIS.

AUTOMATIC GONG-BELL.

SPECIFICATION forming part of Letters Patent No. 659,327, dated October 9, 1900.

Application filed June 20, 1900. Serial No. 20,976. (No model.)

To all whom it may concern:

Be it known that I, EDWARD D. STACY, a citizen of the United States, residing at Chicago, county of Cook, and State of Illinois, have invented certain new and useful Improvements in Automatic Gong-Bells; and I do hereby declare the following to be a full, clear, and exact description, such as will enable persons skilled in the art to which it applies to make and use the same.

My invention relates to improvements in mechanically-operated gong-bells, and it is especially designed to be used in connection with vehicles. It is of that class of bells where-in the motive power to operate the bell is produced by the motion of the vehicle.

In the accompanying drawings, Figure 1 shows my bell attached to a bicycle. Fig. 2 is a bracket by means of which the bell is attached to the forks of the bicycle. Fig. 3 is an end view of the said bracket. Fig. 4 is a plan view of the bell with the gong removed. Fig. 5 is a view from the bottom of the bell. Fig. 6 is a section through line 6-6 of Fig. 4. Fig. 7 shows a carriage and a wheel thereof with my bell attached thereto. Fig. 8 is a side view of the same. Fig. 9 is an adjustable bracket by means of which the bell is fixed to the carriage part. Fig. 10 is a side elevation of the said bracket.

In all the figures the same letters of reference are used to designate similar parts.

B is a gong-bell.

b' is a casting or base-piece for holding the mechanism for operating the clapper b⁷.

b⁵ is a spring surrounding the shaft b³, to which the clapper b⁷ is attached. This spring has an abutment on the supporting-bracket b⁴, through which the shaft passes loosely. It has another abutment on the piece b⁶, which is fixed to the shaft. Spring b⁹ also surrounds the shaft and has an abutment on the bracket b⁵ and the piece b⁶. A shaft b¹² is rotatively supported in the housing b² at right angles to the shaft b³. A rotatable cam b¹³ is fixed to the shaft b¹² under the piece b⁶. The housing b² also surrounds the cam b¹³. The piece b⁶ is in the path of the cam b¹³, and when the shaft to which the latter is fixed is rotated the spring b⁹ is compressed, and when the cam b¹³ passes the piece b⁶ the shaft b³ will be driven

by the spring b⁹ against the inside of the gong b for the purpose of vibrating and sounding the same. Gear-wheel b¹⁴ (or a friction-wheel may be used) is fixed to the shaft b¹² for the purpose of rotating it. The spring b⁸ is designed to bring the clapper b⁷ back out of contact with the gong after the blow has been struck, so as to leave the gong free to vibrate. A bracket b¹⁰ rises above the frame b' of the bell and is adapted to support the gong in position by means of the screw b¹¹. An arm a³ (shown in Figs. 2 and 3) is adapted to support the bell on one of the forks of a bicycle-frame, as shown in Fig. 1. The arm is attached to the bracket b¹⁶ b¹⁷ of the frame b' by means of a bolt that will pass through the said bracket and the perforation a⁴ of the arm a³. The arm a³ is fixed to the bicycle-fork by means of a forked end a⁵ a⁶ and a bolt for holding them together.

An arm b¹⁵ extends from the frame b' of the bell B for the purpose of bodily raising and lowering the bell upon the pivot a⁴ of the arm a³.

The bell is placed on the bicycle so that the friction-pulley b¹⁴ is located immediately above the center of the bicycle-tire a of the wheel A.

A lever a' may be fixed to the bicycle handle-bar, such as is usually used for operating the brake of a bicycle, and a rod a² thereof may be attached to the arm b¹⁵ of the bell. The open spiral spring which surrounds the rod a² will hold the bell in an elevated position, so that the pulley b¹⁴ will be normally out of contact with the wheel a until the handle a' is depressed for the purpose of sounding the alarm, in which event the pulley b¹⁴ will be rotated when it comes in contact with the tire a of the wheel, and the bell will continue to ring loudly until the handle a' is again released. The power for rotating the shaft b¹² of course is secured by the contact of the pulley b¹⁴ with the tire a of the wheel.

I have shown in Fig. 7 a means for attaching my bell to a carriage or other vehicle.

C is an ordinary vehicle-wheel. c is a gear which is fixed to the spokes of the said wheel between the hub and the rim thereof. c' is a pinion that is adapted to mesh into the said gear and which is fixed to the shaft b¹².

*c*⁶ is a bracket to which the bell is hinged, at *c*¹³, in the same manner that it is attached to the bracket *a*³.

For the purpose of guiding the shaft *b*¹² a slot *c*¹⁴ is made in the opposite end of the bracket. A spring *b*¹⁸ is adapted to hold the shaft against the upper limit of the said slot and to hold the bell in an elevated position, so that the pinion *c*' will be normally out of contact with the gear-wheel *c*. A treadle and vertical rod *c*¹² is attached to the arm *c*¹⁵ of the bell for the purpose of compressing the spring *b*¹⁸, and thereby bringing the pinion *c*' into contact with the gear *c* for the purpose of revolving the shaft *b*¹² and sounding the alarm.

The bell is attached to the vehicle by means of the clip *c*³, which is adapted to straddle the axle *c*² and to be held in position by means of the plate *c*¹⁰ and the nut *c*¹¹, as shown in the various figures. The bracket *c*⁶ is supported upon a piece *c*⁵, which latter is guided between guides *c*⁷ of the bracket *c*⁶ and is held in position by means of the nut and stud *c*⁸. Slot *c*⁹ is cut in the piece *c*⁵ for the purpose of adjustment. The piece *c*⁵ is supported upon a pivot *c*⁴ between the piece *c*⁸ and *c*⁵, whereby the bell may be inclined forward or backward, as the case may require, and then fixed in position.

Instead of the gear *c* and the pinion *c*' a friction-wheel may be used, and a friction-pinion may also be employed in lieu of the pinion *c*', such as shown in Figs. 1 and 4.

The method of operation is plainly evident from the drawings and foregoing description.

When it is desirable to ring the bell, it is only necessary to revolve the shaft *b*¹², when the cam *c*¹³ by displacing the shaft *b*³ and the clapper *b*⁷ will compress the spring *b*⁹, after which the shaft *b*³ will be relieved by the cam *b*¹³, having passed beyond the piece *b*⁶. The shaft propelled by the effect of the resilience of the spring *b*⁹ strikes the gong a blow, and at each and every revolution of the shaft *b*¹²

a blow will be struck upon the gong. For the purpose of revolving the shaft *b*¹² it is only necessary to bring it into rotatable communication with some portion of the rotating part of the vehicle. I have shown a means 50 by which this may be done in connection with a bicycle and also in connection with a vehicle, such as a carriage or the like.

Having described my invention, what I claim as new, and desire to secure by Letters 55 Patent of the United States, is—

1. An automatic alarm-bell comprising a base-plate, a gong mounted over the said base-plate, a horizontal shaft supported in the base-plate under said gong, one end of said shaft adapted to be impelled against the side of said gong, an open helical spring surrounding said shaft, between said shaft-supports, another similar spring surrounding said shaft for holding said shaft normally out of contact with said gong, a cam for compressing the first said spring, a shaft to which the said cam is fixed and a housing depending from the said base under the said gong for the said shaft and cam, substantially as set forth. 70

2. An automatic alarm-bell comprising a base-plate, a gong mounted over the said base-plate, a projectile under said gong for striking said gong, a spring for holding said projectile out of contact with said gong, a spring 75 for propelling said projectile, a cam adapted to be rotated for compressing the latter spring, a shaft to which said cam is attached, a housing in the said base for covering the said cam and shaft, and a means associated with a 80 moving vehicle for rotating said shaft, substantially as set forth.

In testimony whereof I have signed this specification, in the presence of two subscribing witnesses, this 16th day of June A. D. 85 1900.

EDWARD D. STACY.
